UNITED STATES PATENT OFFICE.

WILLIAM ROLAND ROOTE, OF GUELPH, ONTARIO, CANADA.

TOP-REST FOR CARRIAGES.

No. 874,794.

Specification of Letters Patent.

Patented Dec. 24, 1907.

Application filed July 17, 1907. Serial No. 384,226.

To all whom it may concern:

Be it known that I, WILLIAM R. ROOTE, citizen of Canada, residing at Guelph, in the Province of Ontario and Dominion of Canada, have invented new and useful Improvements in Top-Rests for Carriages, of which the following is a specification.

My invention pertains to top rests for buggies and other carriages; and it consists in the inexpensive, easily applied, light and neatly appearing top rest hereinafter described and claimed.

In the drawings accompanying and forming part of this specification: Figure 1 is a view partly in elevation and partly in section, illustrating my novel top rest as properly arranged relative to the rail, top and top locking member of a carriage. Fig. 2 is a perspective view of the top rest, removed. Fig. 3 is a transverse section of the said rest.

Similar letters designate corresponding parts in all of the views of the drawings, referring to which:

A is a rail of a carriage, having a lateral projection *a*, of rectangular form in cross-section, which is preferably tapered toward its outer end and is reduced and threaded at such end to receive a top locking member B and a nut C.

D is so much of the bow of a carriage top as is necessary to illustrate the relative arrangement and utility of my novel top rest, and E is the said top rest as a whole. This rest E is made up of a sleeve-like body *c* which is of rectangular form in cross-section, and is preferably, though not necessarily, tapered toward its outer end to conform to the tapered projection *a*, and a cushion *d*, of rubber or analogous material, held in and carried by the sleeve-like body *c*.

In this connection I desire to state that when the lateral projection *a* of the rail A is of even size throughout its length, the sleeve-like body *c* of my novel top rest may be made of even transverse size throughout its length without involving departure from the scope of my invention as claimed. The sleeve-like body *c* of the rest E is formed of a single piece of thin and resilient sheet-metal and is of channel form in cross-section—

i. e., has a bottom wall *e* and side walls *f*, and it is provided on the upper edges of its side walls with inwardly directed flanges *g* for a purpose which will presently appear. The cushion *d* of the rest E is increased in width

at its base to form side flanges *h*, and is arranged relative to the sleeve-like body *c* in the manner best shown in Figs. 2 and 3.

In assembling the parts of my novel rest the side walls *f* of the sleeve-like body are sprung slightly outward and are thereby placed under tension, and the cushion *d* is slid endwise into engagement with the sleeve-like body so that its side flanges *h* rest under the flanges *g* of the body. The side walls *f* of the body are then released, when, as will be readily apparent, they will spring inward and in that way will force and hold the flanges *g* into engagement with the cushion *d* at points immediately above the cushion flanges *h*. From this it follows that the sleeve-like body *c* of my novel rest is adapted to positively hold the cushion *d* without the assistance of extraneous means, and consequently the rest as a whole is at once strong and durable and compact and slightly in appearance, especially when the exterior of the sleeve-like body is japanned, nickel-plated or otherwise embellished. It also follows that when removed from the lateral projections *a* of a carriage, my novel rest E is adapted to be conveniently handled with the same facility as an article formed of a single piece of material.

My novel rest is applied as shown in Fig. 1—that is to say, the sleeve-like body *c* is slipped on the lateral projection *a* of the rail A so that the base of the cushion *d* is crowded against the upper side of the projection *a*, this in order to make the cushion serve the purpose of effectually preventing rattling or shaking of the rest on the said projection *a*. The top locking member B and the nut C are then placed in position in the order named, when, as will be readily apparent, the rest E will be securely retained on the lateral projection *a*. The cushion *d* of the rest is of course arranged at the upper side thereof, and hence will be opposed to and will support the bow D of the top B when the top is lowered with the result that the said bow will not be marred or otherwise injured.

While the body *c* of my novel rest E is of general rectangular form in cross-section, it will be observed by reference to Fig. 3 that the side walls *f* of said body are slightly inclined outward from the bottom wall *e* thereof. From this it follows that the said side walls are under tension and have a tend-

ency to spring inward, and consequently the inwardly directed flanges *g* are enabled to firmly grip and securely hold the cushion *d*.

Having described my invention, what I claim and desire to secure by Letters-Patent, is:

The combination of a carriage rail having a lateral projection of rectangular form in cross-section, a top-locking member and a retaining device secured on the outer portion of the said lateral projection, a top bow, and a rest for the said bow interposed between the top-locking member and the carriage rail; the said rest comprising a sleeve-like body, of general rectangular form in cross-section, receiving the lateral projection of the rail and formed of a single piece of thin and resilient sheet metal and having a bottom wall *e* and side walls *f* inclined slightly

outward from said bottom wall, whereby they are put under tension and have a tendency to spring inward, and also having inwardly directed flanges *g* on the upper portions of the side walls *f*, and a cushion having base flanges arranged under the flanges of the body and between the latter flanges and the lateral projection of the carriage rail, and also having a portion extending upward between the flanges *g* and above the sleeve-like body.

In testimony whereof I have hereunto set my hand in presence of two subscribing witnesses.

WILLIAM ROLAND ROOTE.
